No. 33,336.

Patented Oct. 9, 1900.

O. M. DEEMER.

BRACKET FOR ROTARY BRUSHES.

(Application filed July 23, 1900.)

DESIGN.

UNITED STATES PATENT OFFICE.

ORA M. DEEMER, OF GILMORE, NEBRASKA.

DESIGN FOR A BRACKET FOR ROTARY BRUSHES.

SPECIFICATION forming part of Design No. 33,336, dated October 9, 1900.

Application filed July 23, 1900. Serial No. 24,609. Term of patent 7 years.

To all whom it may concern:

Be it known that I, ORA M. DEEMER, a citizen of the United States, residing at Gilmore, Sarpy county, Nebraska, have invented and 5 produced a new and original Design for a Bracket for Rotary Brushes, of which the following is a specification, reference being had to the accompanying drawings, forming part thereof.

10 In the drawings, Figure 1 shows the bracket in plan view. Fig. 2 is a side elevation thereof, and Fig. 3 is an end view.

As shown in the figures, the bracket is generally of bifurcated form and has a shank

a, with the forked parts b extending therefrom. Ears c rise from the forked parts near the outer end thereof, and these ears have openings d, as shown in Fig. 2.

Fig. 3 shows the bracket in end view, illustrating openings in the corners of the fork. 20

Having thus described my invention, what I claim is—

The design for a bracket for rotary brushes as herein shown and described.

ORA M. DEEMER.
